MERCURY INTERRUPTER

William S. Brian, Owensboro, Ky., assignor to
 General Motors Corporation, Detroit, Mich., a
 corporation of Delaware

Application November 19, 1938, Serial No. 241,383

3 Claims. (Cl. 200—113)

This invention relates to circuit interrupters and more specifically to means for automatically periodically interrupting current flow for changing current or voltage characteristics in direct current circuits.

There are of course many instances in which it is desired to operate devices from a direct current source which require different voltage or current than that available, or perhaps may require a pulsating uni-directional current instead of a constant direct current flow. One illustration of such a condition or plurality of conditions occurs in automotive vehicles where it is necessary to supply many accessories such as clocks or radios with power from the storage battery having a given potential or perhaps to provide power for some of the essential operating parts of the vehicle from said same battery such as, for example, the fuel pump in which instance it is necessary to provide a pulsating current.

It is a basic fact that we cannot change the voltage or current ratio of direct current. We can, however, by interrupting such a current, obtain a pulsating direct current which we can use in many instances exactly as we use alternating current and it is for all practical purposes a one-half wave alternating current. With this pulsating current we may change the current and voltage ratios as desired. These of course are known facts and various means have been developed for periodically interrupting or breaking the current from a direct current source, one of the better known devices being a vibrator such as is used for power supply in an automotive radio receiving set. These devices however utilize mechanical movement and are therefore subject to deterioration both of the switch points and the mechanical vibrating structure.

It is therefore an object of my invention to provide means for automatically interrupting a direct current to provide a more flexible pulsating direct current for any use.

It is a further object of my invention to provide such a current interrupter as shall be substantially insensitive to deterioration and have long life.

It is a further object of my invention to provide such a current interrupter as shall be very simple in construction and relatively easy to manufacture and use.

When a certain material is utilized as a conductor of electric current, if this material is changed from one physical condition to another it frequently ceases to be a conductor, at least at the particular potential applied, and therefore

the circuit is broken. Therefore I have discovered that if a quantity of mercury is taken and a portion of said quantity is caused to be reduced to relatively small cross section area and current is passed therethrough, that what is apparently the heating effect or I^2R loss through this particular portion will cause, if properly controlled, the mercury to vaporize thus breaking the circuit. However, as soon as the circuit is broken 10 the source of heat ceases and the mercury vapor condenses to again recomplete the circuit which may again immediately recycle. Thus, if we form a shell of insulating material, and place therein a body of mercury, said shell having a 15 form of an hour glass, the mercury within the restricted portion will upon a passage of a certain required current vaporize, thus breaking the circuit from one large pool of mercury to the other, but this will immediately recondense to 20 reform the circuit and thus we have an automatic periodic circuit interrupter.

With the above explanation and objects in mind, my invention will be better understood by reference to the following specification and 25 claims and illustrations in the accompanying drawing, in which:

Figure 1 is a vertical section through one of the interrupters of the above identified hour glass type.

Figure 2 is a vertical section through a modified form of the same type of interrupter.

Figure 3 is a vertical section through an internally heated orifice type.

While these various types of interrupters are 30 herein shown as comprising a glass outer envelope, it is to be understood that any insulating envelope may be used and it is only for illustrative purposes that these are shown as being composed of glass and it is also only necessary in this 35 type of interrupter to form the neck or orifice portion of insulating material for operative purposes if it is desired to do so as the two end portions act as a whole as electrodes in any event.

40 Referring now more specifically to Figure 1, an outer shell 2 is shown whose vertical section is substantially that of an hour glass providing an upper chamber 4 and a lower large chamber 6 having a restricted area or orifice 8 therebetween. Two electrodes 10 and 12 are sealed into the upper and lower chambers respectively. There is also sealed within the lower chamber, the orifice and a portion of the upper chamber 45 a body of mercury 14. Thus as a particular potential is applied between 10 and 12, current will

flow through the body of mercury in the upper chamber, through the body of mercury in the orifice 8, and through the mercury in the lower chamber to complete the circuit between these electrodes.

Due to the passage of this current, however, the mercury in the orifice 8 is heated to such a point that a small globule of mercury vapor is formed in this orifice which causes a separation of the two bodies of mercury and thus a cessation of the current flowing between the two. This cessation however removes the source of heating and due to this and to the pressure of the mercury on the globule the same condenses reestablishing the circuit so that current may immediately pass and the device will go through the same cycle. The area of the orifice of course determines the range of potentials applied to the electrodes 10 and 12 which will operate the device as desired.

If it is desired to operate on a lower potential or current flow there may be applied to the orifice a small heating device such as shown at 16 in Figure 2 connected to a power supply which will raise the normal or ambient temperature of the mercury within the orifice and a smaller amount of heat will be required of the current flow to operate the device. Otherwise the device shown in Figure 2 is exactly the same as that shown in Figure 1.

The same results may be obtained by providing a structure such as that shown in Figure 3 in which there is provided an outer insulating shell 18 having an orifice 20 and being sealed with a pool of mercury 22 up to a certain desired level. Extending down through the central portion of the upper cavity and through the orifice is a rod of glass or other insulating material 24 within which is sealed an electrode 26 of comparatively high resistance, said electrode extending from the lower end of the insulating member 24 as shown at 28 to form a contact with the mercury pool in the lower chamber. There is also sealed in the upper portion a second electrode 30 adapted to contact the mercury 22. The flow in this instance is from electrode 26, through tip 28, mercury pool 22, to electrode 30. It will be noted that the mercury in the restricted area 20 is again in series and will be heated as before. However in this instance we have the added heating effect due to the flow of current through the electrode 26 in the orifice for, as before stated, this is of substantially high resistant material

and the I^2R loss will provide additional heat so that this heat will aid the heat due to the series current in the mercury somewhat similar to the action of the external heater shown in Figure 2. Otherwise the operation is the same.

In order to design these interrupters to operate most satisfactorily on any given frequency band, the following factors should be considered:

1. Mercury pressure or height of column within the shell or casing.
  2. The operating temperature of the mercury.
  3. The cross sectional area of the orifice.
- By properly proportioning these satisfactory results will be obtained in combination with the external circuit.
- 15 I claim:
1. In a circuit interrupter, two mercury pools, means for restricting a body of mercury interconnecting the two pools, means for applying a potential difference across the two pools to cause current flow therethrough and through the restricted mercury portion to cause heating and vaporization of the mercury and additional means for heating the restricted portion of mercury comprising a member immersed in and insulated from the restricted portion of mercury and having a comparatively high I^2R drop.
  - 20 2. In a circuit interrupter, an insulating casing having a plurality of bulbous cavities therein and a restriction connecting the same, mercury in each cavity and through the restriction to join the two larger bodies, an electrode terminating in each large body of mercury supported by the casing, one of said electrodes extending through the restricted portion, and means insulating the electrode within the restricted portion whereby no contact is made between the electrode and the mercury therein.
  - 25 3. In a circuit interrupter, a casing, a plurality of pools of mercury supported thereby, a restricted portion interconnecting the pools, electrodes immersed in each pool supported by the casing whereby current is caused to flow through the mercury in the restricted area to heat and vaporize the same, one electrode extending through the restricted area, insulating means separating the electrode from the mercury within the restricted portion whereby the heat generated by the passage of current through the last named electrode will be transmitted to the mercury in the restricted portion and assist in the vaporization and interrupted operation.

WILLIAM S. BRIAN.
